UNITED STATES PATENT OFFICE.

JAMES S. COPELAND, OF HARTFORD, CONNECTICUT, ASSIGNOR TO THE POPE MANUFACTURING COMPANY, OF SAME PLACE AND PORTLAND, MAINE.

DESIGN FOR A BICYCLE-FRAME.

SPECIFICATION forming part of Design No. 28,588, dated May 10, 1898.

Application filed March 21, 1898. Serial No. 674,687. Term of patent 14 years.

To all whom it may concern:

Be it known that I, JAMES S. COPELAND, a citizen of the United States, and a resident of Hartford, in the county of Hartford and State 5 of Connecticut, have invented and produced a new and original Design for a Frame for Bicycles; and I do hereby declare the following, when taken in connection with the accompanying drawings and letters of reference 10 marked thereon, to be a full, clear, and exact description of the same, and said drawings constitute part of this specification, and represent, in—

Figure 1, a view in side elevation of the 15 frame showing my design, and in Fig. 2 a detail top view of a portion of the lower rear fork.

My invention relates to a design for a frame for bicycles; and said invention consists in 20 the configuration of the structure, as herein-after described, and shown in the accompanying drawings.

The structure consists of the socket-head *a* and frame-upright *b*, the first being shorter 25 than the latter, which joins the crank-bracket *e*. These two members are united by the lower center tube *c* and upper center tube *d*, the latter of which forms part of the front portion of the frame and extends from the 30 upper part of the socket-head *a* in a straight line and then on a curve to a point where it meets the frame-upright *b*. The lower center tube *c* extends from the lower part of the

socket-head *a* on a reverse curve to a point where it joins the crank-bracket *e*. The 35 crank-bracket *e* is cylindrical in outline, with an enlarged end *e'* and a tapered portion *e''*, merging into the lower rear fork *f*. The two members *c* and *d* are united by transverse braces *g* and *h*. The rear portion of the frame 40 is of triangular outline, bounded by the frame-upright *b*, the lower rear fork *f*, and the upper rear fork *g*. At the junction of the members *g* and *f* appears a bulbous part *n*, located within an inclosing frame. Behind the rear 45 portion *i* of this frame, when seen in side view, appears a circular figure *k*, which in top view presents an oblong figure with rounded edges *k'* *k''*. The front portion *l* of the inclosing frame terminates in the form of a cylinder connecting the frame and the bulb *n*. 50

The essential feature of my design consists in the front portion, as shown, with the triangular rear portion having the bulbous enlargement located within an inclosing frame 55 at an angle thereof.

I claim—

The design for a frame for bicycles substantially as shown and described.

In testimony whereof I have signed this 60 specification in the presence of two subscribing witnesses.

JAMES S. COPELAND.
